UNITED STATES PATENT OFFICE.

DAVID MANUEL AND CALVIN F. MANUEL, OF BOSTON, MASSACHUSETTS.

PAPER BAG.

Specification forming part of Letters Patent No. 71,398, dated November 26, 1867.

To all whom it may concern:

Be it known that we, DAVID MANUEL and CALVIN F. MANUEL, of Boston, in the county of Suffolk and State of Massachusetts, have invented a new and useful Improvement in Paper Bags; and we do hereby declare that the following is a full, clear, and exact description thereof, which will enable others skilled in the art to make and use the same, reference being had to the accompanying drawings, forming part of this specification, in which—

Figure 1 is a plan of the cut or pattern of the bag before folding and pasting. Fig. 2 is a plan of the bag half-folded for receiving the paste. Fig. 3 is a plan of the bag when pasted.

Similar letters of reference indicate like parts.

This invention relates to an improved mode of making paper bags; and consists in cutting the material out and folding the edges together in such a manner as to make a conical bag with a flap cap or cover for securing whatever the bag may contain.

The advantage of this bag is found in its extreme simplicity and great economy in the use of material, the application of the material being such that the whole superficies of the paper is utilized in forming a bag of the largest possible dimensions, while the narrow laps employed for folding and pasting the edges together are strong, and the shape of the bag is very convenient for putting things into it and securing them in a neat package or parcel.

The paper is cut into parallelograms, or equilaterally, as shown in Fig. 1, except at one corner, where a point is formed by the apex *a* of a central triangle, *a b c*, by cutting a small triangular piece, *a i o*, on each side of the apex from the flap-pieces *b e a* and *c d a*. The small equal triangular offsets *a i o* thus cut in the pattern of the bag have their

base-lines *o i* parallel with the central diagonal line *c d* of the square, so that when the side flaps *b e o i* and *c d o i* are folded down and lapped to form a bag, as shown in Fig. 3, small spaces *s s* of single paper will be left for the lap of the apex *a* to lie upon, and thus make a strong and perfect attachment at the bottom or small end of the conical bag which will be formed.

In order to fold and paste the bag together, the side flap-piece *c d o i* is turned back on the line *a c* of the triangle *a b c*, the edge *o d* extending a little over the central line *a f*, and when the side flap is in this position a narrow strip, indicated in red near the edge *o d*, and extending to the point of the apex *a*, is covered with a coat of paste in the ordinary way, upon which is first folded down the other side flap, *b e o i*, and then the apex *a* is turned over and also folded down, as shown in Fig. 3, to complete the bag. The triangular piece *b c f* left forms a cap or cover for the conical bag thus put together.

It will be seen that the point *a i o* may be cut in any desired form for folding over as a closing-cap of the apex of a conical bag without changing its character and office.

Having thus described our invention, we claim as new and desire to secure by Letters Patent—

The triangular paper bag constructed as described, by folding the sides *d e* one upon the other, of the parallelogram cut with the apex *a*, as shown in Fig. 1, in the lines *i c* and *i b*, upon the triangular center described by the lines *a b*, *a c*, and *b c*, and by folding the apex *a* over the said folded sides *e d*, as herein set forth, for the purpose specified.

DAVID MANUEL.
C. F. MANUEL.
